Primary Examiner — Mary Shannon Malley

Assistant Examiner — Christopher John Suarez La Rosa

(57) **CLAIM**

The ornamental design for a portable electronics holster, as shown and described.

DESCRIPTION

FIG. 1 is a front perspective view of the portable electronics holster showing my new design;

FIG. 2 is a front elevation view thereof;

FIG. 3 is a rear elevation view thereof;

FIG. 4 is a left side elevation view thereof, the right-side elevation view being a mirror image thereof;

FIG. 5 is a top plan view thereof;

FIG. 6 is a bottom plan view thereof;

FIG. 7 is a rear perspective view thereof showing the portable electronics holster in use in a first configuration;

FIG. 8 is a rear perspective view, similar to FIG. 7, showing the portable electronics holster in use in second configuration;

FIG. 9 is a rear perspective view, similar to FIG. 7, showing the portable electronics holster in use in a third configuration; and,

FIG. 10 is a front elevation view, similar to FIG. 2, showing the portable electronics holster in use in the second configuration of FIG. 8.

The broken lines in FIGS. 1-6 depict portions of the portable electronics holster that form no part of the claimed design. The broken lines in FIGS. 7-10 depict environmental subject matter that forms no part of the claimed design.

1 Claim, 8 Drawing Sheets
